UNITED STATES PATENT OFFICE.

EDWARD E. RAINY, OF DENVER, COLORADO.

VALVE LIFTER.

Application filed March 1, 1926. Serial No. 91,425.

This invention relates to improvements in valve lifters.

In repairing automobile engines and especially when the valves are to be ground or removed for this or any other purpose, it is necessary to compress the valve springs so that the pins or other means may be removed from the valve stems. In some makes of automobile engines the valve springs are very powerful and can be compressed only by using tools especially constructed for this purpose.

It is the object of this invention to produce a valve compressor which shall be so constructed that it can be employed for compressing the springs on any motor and which shall be adjustable to any size necessary. In addition to this it is a further object of this invention to produce a device that can be readily assembled and disassembled so that it will occupy only a small space and which can therefore be readily packed and carried in the workman's tool box. The above and other object that will become apparent as the description proceeds are attained by means of a construction that will now be described in detail, reference for the purpose being had to the accompanying drawing in which the preferred form of this invention has been shown and in which:

Fig. 1 is a side elevation of the valve lifter, parts being broken away to better disclose the construction, a portion of the valve and valve spring being shown for the purpose of illustrating the manner of using the lifter;

Fig. 2 is a section taken on a line that corresponds to line 2—2, Fig. 3;

Fig. 3 is a section taken on line 3—3, Fig. 2;

Fig. 4 is a section taken on line 4—4, Fig. 1;

Fig. 5 is a section taken on line 5—5, Fig. 2; and

Fig. 6 is a fragmentary plan view looking in the direction of the arrow 6 in Fig. 1.

Numeral 1 indicates a poppet valve of ordinary construction and 2 the valve spring that is to be compressed. As the construction of the engine is immaterial for the purpose of illustrating this invention, it has not been shown but a portion thereof has been indicated by a dotted line that has been designated by numeral 3.

The spring compressor is formed from several parts and consists of a member 4 of U-shaped cross section. This member has

two arms 5 and 6 which extend at right angles to each other. This member is arranged with the base of the U towards the inside. The end of the arm 5 is cut diagonally in the manner indicated by line 7 and terminates in projections 8 that are perforated for the reception of the rivet 9 which is adapted to engage the notches 10 in the bar 11. It will be noted from Fig. 1 that if the end of the arm 5 were cut at right angles instead of on a diagonal that the member 11 could not be moved without first removing the rivet, but by the simple expedient of the diagonal cut it is possible to remove the rivet 9 from the notch 10 by merely moving the bar 11 downwardly out of alignment into the position indicated by the dotted line 12. A flat metal loop 13 encircles the arm 5 and when it is in the position shown in Fig. 1 the part 11 will be positively held against relative movement with arm 5. The outer end of bar 11 is enlarged as indicated by numeral 14 and is provided with a threaded opening 15 for the reception of the threaded tubular member 16. This member has a diametrical slot 17 that extends downwardly from the upper end. A cam 18 is pivoted at 19 and is provided with a handle 20 by means of which it can be rotated about the pivot. The extreme end of the cam 18 is provided with a head or thickened portion 21 which serves as a stop when it engages the bottom of the depression or notch 22. Slidable within the tubular member 16 is a plunger 23 of smaller diameter than the opening in the tubular member. The upper end 24 of this plunger has substantially the same diameter as the opening in the tubular member 16. A shoulder 26 is formed at the lower end of the cylindrical part 24 and this shoulder forms one abutment for the spring 27 whose other end is formed by the ring 28 that is secured to the lower end of the opening in member 16. The spring 27 is under compression and exerts a force tending to move the plunger 23 upwardly. The upper end of the cylindrical portion 24 has a transverse slot 29 within which is pivoted the roller 30 whose periphery is forced against the outer surface of the cam 18 by the action of the spring 27. The cam 18 has a notch 31 near its tip for the reception of the roller 30 (Figs. 1 and 2). It is now evident that when the cam 18 is moved from the position shown in Fig. 1 to that

shown in Fig. 2, the plunger will be projected from the tubular member. Secured to the arm 6 in exactly the same manner as bar 11 is secured to the arm 5 is an angular connecting member 4^a having arms 32 and 33 each of which has notches 10^a for receiving and cooperating with the rivets 9^a. Flat metal loops 13^a surround the arm 6 and the U-shaped connector 34 and operate like the loop 13 to hold the parts in alignment. Secured to the end of the connector 34 is a removable part 35 whose outer end is forked and composed of two arcuate arms 36. Attached to the arms 36 by means of pivots 37 is a U-shaped abutment 38 formed from a piece of metal pressed into an L-shaped cross section. The lower end of the spring 2 rests on the upper surface of the member 38.

Let us now assume that the parts are assembled in the manner shown in Fig. 1 and that it is desired to compress the spring so as to remove the pin or other means that is employed for holding the valve in place. The U-shaped member 38 is placed underneath the lower end of the spring and the sharp end of the plunger 23 is put into position against the upper end of the valve. The handle 20 is now grasped and moved from the position shown in Fig. 1 to that shown in Fig. 2 whereby the cam 18 moves the plunger 23 downwardly and thereby decreases the distance between the end of the plunger and the member 38 thereby compressing the spring.

When the tool is not in use it may be separated into five parts and can then be placed in a tool box along with the other tools of the kit.

I have shown the member 35 as being separate from the part 34 but this is not necessary as they may be formed from a single piece if desired.

When the device is to be used for different makes of engines it may be roughly adjusted by moving the parts 32, 4, 11 and 35 rela-

tive to each other until the device assumes the proper size. By turning the tubular member 16 it may be adjusted to the most desirable position.

50

Having now described my invention what I claim as new is:

1. A valve spring compressor comprising a frame having two parts, each of which has two arms extending at right angles to each other, one of said parts having a channel along its outer surface, which is adapted to receive the other part, the ends of the channeled part, to which the other part is attached being cut diagonally so that the closed side is shorter than the open side, the tips of each of the end portions of said channeled parts being connected by a rivet, the other part having a width substantially equal to the depth of the channel and having its outer edge provided with notches adapted to be engaged by the rivet when the parts are in aligned position and from which the rivets become disengaged when the parts are moved angularly with respect to each other.

60

2. A valve spring compressor composed of five separate relatively movable and adjustable parts, two of which are of bell crank shape and the others substantially straight, one of said bell crank shaped parts having a U-shaped cross section with the open side towards the outside whereby a channel is formed, and the other having a rectangular cross section and being of the proper size to fit the channel of the section having the U-shaped cross section means for holding the two bell crank members together so as to form a frame having parallel side members, a threaded plug, a member adjustably connected with each of said parallel side members, one of said members having a threaded opening, for the reception of the threaded plug and a U-shaped spring engaging means attached to the outer end of the other adjustable member.

70

In testimony whereof I affix my signature.

EDWARD E. RAINY.
